UNITED STATES PATENT OFFICE.

PETER JOHN PEARSON, OF STAVELEY, ALBERTA, CANADA.

PROJECTILE.

1,190,578.

Specification of Letters Patent. Patented July 11, 1916.

Application filed February 3, 1915. Serial No. 6,818.

To all whom it may concern:

Be it known that I, PETER JOHN PEARSON, a citizen of Canada, residing at Staveley, in the Province of Alberta and Dominion of Canada, have invented certain new and useful Improvements in Projectiles, of which the following is a specification.

This invention relates to improvements in projectiles and its object is to produce a projectile provided with an inflammable fluid and with a percussion cap whereby the fluid is ignited when the projectile strikes a resisting object.

With the foregoing and other objects in view the invention consists in the combination and arrangements of parts to be hereinafter fully described in the following specification, pointed out in the claims and illustrated in the accompanying drawings which form a part of said specification and in which—

Figure 1 is a side view of my improved projectile. Fig. 2 is a longitudinal sectional view therethrough. Fig. 3 is a cross section taken on line 3—3 of Fig. 2. Fig. 4 is a longitudinal sectional view showing the projectile at the moment of contact with an object. Fig. 5 is a longitudinal sectional view of a modification. Fig. 6 is a cross section taken on line 6—6 of Fig. 5.

Like reference characters indicate corresponding parts throughout the several views.

Referring to Figs. 1, 2, 3, and 4 the reference numeral 1 designates the shell which is formed with surface grooves 2 and with interior longitudinal openings or perforations 3 adapted to contain an inflammable fluid 4; the ends of the open portions being plugged with metal caps 5. The shell 1 is formed with a shank or stem 6 which extends into a bore formed in the end of the stock 7, a space or cell 8 being formed between the end of the shank 6 and the bottom of the bore in the stock and said cell is adapted to contain an inflammable fluid. Between the end of the stock and the enlarged head of the shell a cell or channel 9 is formed which is connected with the said cell 8 by channels 8^a, and said cell 9 contains an inflammable fluid and is covered or capped by a ring 10, one edge of which is disposed in an annular groove 11 in the head of the shell and the opposite edge of which abuts an annular shoulder 12 formed near the end of the stock. The point or nose

of the shell is provided with an exterior percussion cap 13 which is exploded by contact of the shell with an object thereby igniting the fluid and greatly increasing the force of the blow. The impact of the shell against the object struck will drive the shell completely into the stock closing the channels 8 and 9, displacing the collar 10 and expelling the inflammable fluid which will set fire to the object struck should it be of a combustible nature.

In the modification, Figs. 5 and 6, the shell 1 contains a small bullet 14 and an interior percussion cap 13^a which is exploded by contact with the bullet when the projectile lands or strikes; the cavity between the bullet 14 and the interior wall of the shell being filled with an inflammable fluid which is forced out through the perforations 3^a in the shell at the time of the impact.

What is claimed is:—

1. A projectile comprising a stock formed with a terminal bore, an interiorly perforated shell arranged in the bored end of said stock, caps for said perforated portions, the head of said shell being spaced away from the end of said stock, a ring connecting the head of said shell and said stock, a percussion cap carried by said shell and an inflammable fluid disposed in the perforated portions of said shell and in the spaced portion between the head of said shell and the adjacent end of said stock.

2. A projectile comprising a stock formed with a terminal bore, an interiorly perforated shell comprising a head and a shank, caps for the perforated portions of said shell, the said shank being projected into the end of said stock a distance less than the depth of the bore therein and said head being spaced away from the adjacent end of said stock; said head being formed with an annular groove, an annular shoulder formed upon the end of said stock, a collar connecting said stock and shell and having its lateral edges abutting said shoulder and disposed in the grooved portion of said head, a percussion cap carried by said shell and an inflammable fluid disposed in the perforated portions of said shell and in the spaced portions between said head and stock and between said shank and stock.

3. A projectile comprising a hollow perforated shell, an interior percussion cap for said shell, a bullet arranged in said shell

and spaced away from the nose thereof, an inflammable fluid arranged in the hollowed end of said shell and in the apertured portions thereof and caps for the perforated portions of said shell.

5 In testimony that I claim the foregoing as my own I have hereto affixed my signa-

ture in the presence of two subscribing witnesses.

PETER JOHN PEARSON.
